CLAIM

We claim the ornamental design for a snow protector for vehicle charge port, as shown.

DESCRIPTION

FIG. 1 is a top, front, right side perspective view of a snow protector for vehicle charge port showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom, rear, left side perspective view thereof.

1 Claim, 8 Drawing Sheets
